WEB ROLL SUPPORT

Frederick Lamatsch, Grantwood, N. J., assignor
to Irving Trust Company, permanent trustee
for R. Hoe & Co., Inc., New York, N. Y., a cor-
poration of New York

Application June 6, 1932, Serial No. 615,603

11 Claims. (Cl. 242—68)

This invention relates to improvements in web roll supports adapted to rotatably carry a roll of paper and permit it to be easily unreeled therefrom.

5 This apparatus obviates the use of the usual metal shafts or spindles for the support of rolls of paper, ordinarily known as web rolls. Such spindles extend through the web rolls and are heavy and have to be handled manually for movement into and out of the central tube or core of said rolls, therefore causing extra effort, expense and delay.

On the other hand, the mechanism of this invention obviates the above objections and to these ends it is provided with a pair of rotatable cone members, which project slightly into the ends of the fibre or paper core tube, which forms the central portion of the roll of paper and on which the paper is wound at the paper mill. These core tubes are generally provided with metal ferrules on their end portions, so as to properly receive the cones above referred to and to prevent deformation of the paper core tube or the paper on account of the great weight of the roll and the shocks due to its handling and rotation.

By reason of the simplicity of its construction and operation, this improved apparatus saves time, labor and expense in the interchange of web rolls and it is, therefore, valuable in these respects.

30 It is one of the objects of this invention to provide means whereby a rotatable web roll cone may be quickly and readily engaged with the central tube or core of a new web roll and it also may be speedily and easily withdrawn therefrom when the web roll is exhausted.

It is also the object of this invention to provide mechanism which may be moved quickly to primarily engage and later to promptly disengage the core tube of a web roll.

40 It is also the object of this invention to provide a supplementary and more powerful slow moving means to produce the final effort of engaging the rotatable supporting cone with the central core or tube in a forcible manner as is necessary to insure its desired fixed centrality and firm contact with the ferrule of the core tube. The same powerful slow moving means are operated in the reverse direction to produce the initial effort of withdrawing the supporting cone, on account of its firm engagement with the end or ferrule of the central tube or core of the web roll, after which the quick acting means are used to promptly complete the withdrawal.

55 This permits a new web roll to be speedily, firmly and centrally mounted on a pair of rotatable web supporting cones and when the web is exhausted by unreeeling it, the supports can be readily withdrawn and in readiness for again engaging another new web roll.

60 In cases where the core tubes of the web rolls

are substantially of the same lengths and strengths, it is also possible, by means of this invention, to mount them on their supporting cones by the quick movement only, thus conducing to speed of operation.

5 It is generally better however, to complete the mounting by finally using the slow but powerful longitudinal adjusting means to insure the thorough seating of the supporting cones in the ferrules of the core tubes. A reversal of these operations will withdraw the cones.

It is also an object of the invention to provide a web roll support of generally improved construction, whereby the device is simple, durable and inexpensive in construction, as well as convenient, 15 practical, serviceable and efficient in use.

With the foregoing and other objects in view, which will appear as the description proceeds, the invention resides in the combination and arrangement of parts, and in the details of construction 20 hereinafter described and claimed, it being understood that various changes in the precise embodiment of the invention herein disclosed may be made within the scope of what is claimed without departing from the spirit of the invention.

25 Having thus given a general description of some of the objects of the invention, the two sheets of drawings, attached hereto and forming part hereof will now be referred to as illustrating a preferred embodiment thereof:

Figure 1 is a side elevation of a web roll support with the cone in withdrawn position, and also shows a portion of the web roll adjacent thereto;

Figure 2 is a side elevation similar to Figure 1, but with the web roll supporting cone projecting 35 partially within the end of the cone in operative position;

Figure 3 is a front elevation and partial section on the line 3 of Figure 2 looking in the direction of the arrow; and

40 Figure 4 is a vertical axial section, parts appearing in elevation.

Referring now to the characters of reference on the drawings:

The outer portion of one of the arms of a 45 spider forming part of a reel adapted to carry a plurality of rotatable web rolls and to revolve them successively into operative position, is indicated as 11 and this is provided with an integral hub 12, which forms the supporting frame 50 for the mechanism of this invention.

Mounted in the bore of the hub 12 is an outer sleeve 13, adapted to be moved axially in both directions but restrained from rotation by the feather 14. Within the bore of the sleeve 13 is 55 mounted an inner sleeve 15 which is also adapted to be moved axially therein relatively to the outer sleeve 13 and is restrained from rotation by a feather 16.

The outer sleeve 13 has a slot 17 in its shell 60

and a rotatable stub shaft 18 has an eccentrically positioned crank pin or stud 19 adapted to fit in the slot and to reciprocate the sleeve and the parts attached thereto by the rotation of the shaft.

10 The stub shaft 18 is held in place by an annular washer 20 secured to the hub 12 by tap screws as shown. An operating lever 21 is provided which has its hub mounted on a reduced outer end 22 of the stub shaft 18 and is secured thereto by a key 23, a bolt 24 and a washer 25.

15 The operating lever or crank arm 21 has a handle 26 and a spring projected locking pin 27 which is adapted to be seated in a lower hole 28 to hold a web roll support cone 41 in operative position, or in an upper hole 29 when the support cone is withdrawn and inoperative.

20 Other holes may be provided, in addition to those shown, in order to arrange for different lengths of movement and locking positions of the outer sleeve 13 and its attachments, as will be readily understood.

25 Adjacent to and forming part of the handle is a detent lever 31, mounted on a pivot 32, adapted to withdraw the locking pin 27 from the hole in which its end may be, while the spring surrounding the locking pin is adapted to project it into either of the holes 28 or 29 or others by operating in the customary manner for such an appliance.

30 The internal cone supporting sleeve 15 has an internally screw threaded bore 30 adapted to receive the threaded portion of a screw 33 as illustrated.

35 The screw 33 has an intermediate body portion 34 of reduced diameter and surrounding this is a split washer 35 secured to the sleeve 15 by tap screws as shown, which retains the screw threaded end within the sleeve and limits its movement by contact with its shoulders.

40 The screw 33 has a hand wheel 36, secured on its outer end, and this is provided with a hub 37, while a collar 38 is secured to the unthreaded body of the screw, between which and the hub, an annular plate 39 projects, and as this plate is secured to the outer sleeve 13 by tap screws as shown, the rotations of the hand wheel will slowly but forcibly project or retract the inner sleeve 15 and the web supporting cone 41 that is rotatably mounted on its outer end.

45 A web roll supporting cone 41 is mounted on thrust and ball bearings carried by a reduced end 42 of the inner sleeve 15 and is secured in place by a washer 43 and a bolt 44.

50 This cone 41 is adapted to rotatably carry the web roll 45 which is wound on the core tube 46 which is provided with the usual metal ferrule 47 adapted to reinforce its end in order to protect it against the thrust and expansive force exerted by the cone 41.

55 It should be understood that the other end of the web roll, not shown, has a similar ferrule and a similar mechanism is provided to support it. The companion cone may be rotatably supported on a solid member which replaces the sleeves 13 and 15 and which is moved longitudinally by a crank pin moved by an operating lever similar to that shown at 21. In such case, the hand wheel 36 is not provided on the support for the end of the roll not shown, as the web roll can have one of its ends first mounted thereon and the final adjustment and positioning can be accomplished at the other end of the web roll by the longitudinally and dually adjustable cone of this invention.

70 75 Both cones can however, be moved axially and

simultaneously to the same extent by the motion of the reel to longitudinally adjust the web roll and its margins to the desired registry.

Having thus given a description of the various features of the mechanism a brief résumé of its 5 operation will be of interest.

After the core of a depleted roll has been removed from the reel and a co-operative pair of the reel arms are in non-feeding position, a new web roll is placed between the arms and its core 10 tube ends are aligned with the cones which are then in retracted position as shown in Figure 1. The handle 26 is then grasped, the locking pin 27 is withdrawn and the handle is then rotated a half turn counterclockwise to the position shown 15 in Figure 2. This produces a quick projecting axial movement of the cone 41, as, at this time, the cone is free and easily moved but at the end of this forward movement the cone is in contact with the ferrule 47 of the core tube 46. This half rotation of the handle 26 causes the stud 19 to revolve about the axis of the stub shaft 18 and, as it is connected to the sleeve 13 in the slot 17, it will quickly project the sleeve 13 and its attachments, so that the cone 41 contacts with the ferrule of 25 the core tube 46. After this is done, the handle is locked in the position shown in Figure 3 by the locking bolt entering the recess 28. This operation is performed at both ends of the roll, and thereafter the hand wheel 36 may be turned to 30 slowly and more forcibly seat the cone 41 in and against the ferrule 47.

35 A considerable length of axial movement of the supporting cone 41 is required, owing to the fact that the web rolls are large and heavy and can 40 not be very accurately positioned to receive the supporting cones and therefore must have ample clearance between them to allow successive web rolls to be readily and easily placed in readiness to receive the rotatable supports.

45 It should also be noted that web rolls vary in length to a certain extent so that some are about one quarter of an inch or more longer than others and this requires longitudinal adjustment of the supporting cone.

50 In cases, however, where the successive core tubes of the web rolls are substantially of the same lengths and strengths, it is possible to mount such rolls on their supporting cones by the sole motion of projection occasioned by the rotation of the handle 26, which causes the quick forward movement of the sleeve 13 and its attached parts.

55 It may be preferable, however, to complete the contact of the web supporting cone with the end of the core tube by a slight rotation of the hand wheel 36 which compensates for slight differences in the lengths of the web rolls and insures more forcible final pressure, in order to prevent relative slippage or displacement of the web roll.

60 It will thus be seen that this invention provides quick, ready and also powerful means for engaging the rotatable web roll supporting cones with the ends of the core tube and this facilitates ease, speed and economy of operation and conduces to increased output.

65 What I claim is:

70 75 1. A frame, an outer sleeve slidably mounted therein, a shaft mounted in the frame and provided with a crank pin having rotating means adapted to quickly reciprocate said outer sleeve and its attachments, an inner sleeve slidably mounted in said outer sleeve, a rotatable web roll support cone on said inner sleeve, and a screw rotatably mounted on said outer sleeve and

adapted to slowly and axially project and retract said inner sleeve.

2. A frame, an outer sleeve slidably mounted therein, a shaft provided with a crank pin, rotating and locking means, mounted in the frame and adapted to quickly reciprocate said sleeve, an inner sleeve slidably mounted in said outer sleeve and provided with a rotatable web roll support cone carried thereby, a screw axially fixed and 10 rotatably mounted on said outer sleeve, an internal screw thread in said inner sleeve in which the threaded portion of said screw operates, and means for rotating said screw whereby the inner sleeve and the support cone carried thereby may 15 be slowly but forcibly adjusted axially.

3. A frame, a non-rotative outer sleeve slidably mounted therein, said sleeve having a slot therein, a shaft mounted in the frame and provided with an eccentric pin located in the slot 20 in said sleeve, rotating means for said shaft adapted to quickly reciprocate said outer sleeve, an inner sleeve slidably mounted in said outer sleeve and provided with a rotatable web supporting cone carried thereby, a screw rotatably 25 mounted on and fixed axially of said outer sleeve, an internal screw thread in said inner sleeve in which said screw operates, and means for rotating said screw, whereby the inner sleeve and the supporting cone are slowly but forcibly projected 30 or retracted.

4. In a chuck mechanism for supporting a web roll including in combination, a framing, an outer sleeve having a slideable but non-rotatable movement within said framing, said sleeve having a slot therein, an inner sleeve having a slideable but non-rotatable movement within said outer sleeve, a web supporting cone rotatably mounted on said inner sleeve, a crank shaft mounted in said frame having an eccentrically positioned crank pin projecting from one end thereof and in engagement with the slot in the said outer sleeve, an operating lever secured to the opposite end of said crank shaft to rotate same and thereby quickly advance or retract the web supporting cone, locking means 45 to retain said cone in either position, and means for effecting a fine adjustment of the cone position independently of the outer sleeve.

5. In a chuck mechanism for supporting a web roll including in combination, a framing having 50 holes formed therein, an outer sleeve having a slideable but non-rotatable movement within said framing, said sleeve having a slot therein, an inner sleeve having a slideable but non-rotatable movement within said outer sleeve, a web supporting cone rotatably mounted on said inner sleeve, a crank shaft mounted in said frame having an eccentrically positioned crank pin projecting from one end thereof and in engagement with the slot in the said outer sleeve, an operating lever secured to the opposite end of said crank shaft to rotate same and thereby quickly advance or retract the web supporting cone, a locking pin 55 on said operating lever adapted to engage the holes in the framing to retain said cone in a predetermined position, and a hand wheel for effecting an axial movement of the inner sleeve and cone mounted thereon, independently of the outer sleeve.

6. A web roll support including a frame, a sleeve slideable longitudinally in the frame, a roll supporting member carried by the sleeve, means

for locking the sleeve against rotation relative to the frame, a manually movable crank pin operably engaging the sleeve to move it longitudinally thereby moving the roll supporting member to and from engagement with the core of the web roll to operably support or release the web roll.

7. A web roll support including a frame, a sleeve slideable longitudinally in the frame, a roll supporting member rotatably carried by the sleeve, means for locking the sleeve against rotation relative to the frame, a manually movable crank pin operably engaging the sleeve to move it longitudinally thereby moving the roll supporting member to and from engagement with the core of the web roll to operably support or release the web roll.

8. A web roll support including a frame, a sleeve slideable longitudinally in the frame, a roll supporting member operably carried by the sleeve, 20 means for locking the sleeve against rotation relative to the frame, a manually rotatable shaft operably mounted in the frame, a crank pin on said shaft operably engaging the sleeve to move it longitudinally when the shaft is rotated, thereby moving the roll supporting member to and from engagement with the core of the web roll to operably support or release the web roll, means for limiting the rotation of the shaft, and means for locking the shaft in different rotative positions.

9. A web roll support including a frame, a sleeve slideable longitudinally in the frame, a roll supporting member operably supported by the sleeve and movable longitudinally relative to the sleeve, means for locking the sleeve against rotation relative to the frame, a manually movable crank pin operably engaging the sleeve to move it longitudinally thereby moving the roll supporting member to and from engagement with the core of the web roll to operably support or release the web roll, and means independent of the crank pin for moving the roll supporting member longitudinally relative to the sleeve to adjust the roll supporting member.

10. A web roll support including a frame, a sleeve slideably supported by the frame, said sleeve having a slot therein, a shaft operably mounted in the frame, an eccentric pin carried by the shaft and projecting into the slot, a roll supporting 50 member carried by the sleeve, and manually operable means for rotating the shaft to cause the eccentric pin to slide the sleeve relative to the frame thereby moving the roll supporting member to and from engagement with the core of the web 55 roll to operably support or release the web roll.

11. A web roll support including a frame, a sleeve slideably supported by the frame, said sleeve having a slot therein, a shaft mounted in the frame, an eccentric pin carried by the shaft and 60 projecting into the slot, a roll supporting member operably supported by the sleeve and slideable relative thereto, manually operable means for rotating the shaft to cause the eccentric pin to slide the sleeve relative to the frame thereby moving 65 the roll supporting member to and from engagement with the core of the web roll, and means independent of the eccentric pin for sliding the roll supporting member relative to the sleeve to adjust the roll supporting member.
